UNITED STATES PATENT OFFICE.

DAVID P. DAVIS, OF JERSEY CITY, NEW JERSEY.

HYDRAULIC ELEVATOR.

SPECIFICATION forming part of Letters Patent No. 229,591, dated July 6, 1880.

Application filed January 17, 1880.

To all whom it may concern:

Be it known that I, DAVID P. DAVIS, of Jersey City, in the county of Hudson and State of New Jersey, have invented an Improvement in Hydraulic Elevators, of which the following is a specification.

Hydraulic elevators have been made in which there is a cylinder and piston connected by a rod and multiplying-pulleys to the car, the water being supplied at one side of the piston to raise the car, and escaping as the car is lowered, the speed of movement depending on the opening of the inlet and outlet valves, and in some instances the pressure from an elevated tank has been used, and in other instances the water has been pumped into the cylinder.

My invention, as distinguished from others, relates to transferring the water from one side 20 of the piston to the other by the action of a pump, and keeping the passages and cylinders entirely full of water by supply from a small reservoir that makes up loss from leakage, whereby there cannot be any vacuum or 25 air-space, and sudden motion of the piston or the car in either direction is prevented.

I also combine with the elevator-cylinder and pump-passage ways and valves arranged in such a manner that the pump may continue 30 to run in one direction, and by moving the valves the water is taken from below the piston and transferred to the cylinder above the piston, thus moving the piston in one direction; or else the water is transferred from 35 above the piston to the cylinder below the piston, moving the piston the other way; or else the water is allowed to churn around in the pump and pipes without passing into the hydraulic cylinder, and hence the piston and car 40 are held stationary. In all these cases the power exerted will only be in proportion to the weight to be raised, because the governor of the engine will only supply the steam needed to run the pump at a given speed, and this 45 speed will be maintained by a lower pressure of steam with a light load than with a heavy load. A saving will therefore be effected by my improvement over and above the devices in which the water has to be pumped up to a 50 given height, and there is as much water used with a light load as with a heavy load.

My invention is also to be distinguished from those elevators in which the car is raised by a pump that is used to force the water into the hydraulic cylinder, and the lowering of 55 the car is controlled by the escape of water into a tank; and it is also to be distinguished from elevators in which the weight of the car in descending is made to operate a pump, the speed of which is controlled by valves that 60 regulate the discharge of the water from the pump.

In the drawings, Figure 1 is an elevation of the apparatus. Fig. 2 is an elevation at right angles to Fig. 1, without the engine; and Fig. 65 3 is a section at the line *xx* through the valves.

The cylinder *a* is of suitable size, according to the character of the elevator, and the piston-rod *r* from the piston is connected by suitable ropes and multiplying-pulleys to the 70 car or platform to be raised.

The engine is represented at *C*, and the same may be of any desired character, and the pump *b* is represented as a rotary pump. It may, however, be a double-acting pump of any 75 character to insure uniformity in the action on the water.

The pipes *f* and *f'* pass from the ends of the cylinder *a* to the water-ways of the pump. These water-ways are shown more clearly in 80 Fig. 3, wherein the valves *d* and *e* are introduced within cylinders at the junction of the branch pipes *f*² from the pipe *f*, and *f*³ from the pipe *f'*, and the pipe *n* *n'* from the pump.

The cylindrical valves *d* and *e* are within cylindrical cases, and the stems of the valves pass through glands or stuffing-boxes. On the stem of the valve *d* there is a wheel, *g*, that is operated by the hand-rope in the elevator, and the connecting-rod *h* and crank *h'* to the 90 stem of the valve *e* operate so that the two cylinder-valves are moved at the same time by the elevator-rope. There is a pipe, *i*, passing from the valve-cylinder *d* to the valve-cylinder *e*. The induction-way *n* passes from the 95 inside of the cylinder-valve *e* to the pump, and the induction-pipe *n'* terminates in the cylinder-valve *d*.

The action is as follows: When the valves *d* and *e* are in the positions shown in Fig. 3 100 the water passing from the pump goes along *n'* into *d*, thence by the ports 1 2, pipe *i*, and

ports 3 and 4, into the valve *e* and back to the pump. At this time the cylindrical valves close *d* and *e*, the ports 5, 6, 7, and 8, and water cannot pass by the pipes *f* or *f'*, and the cylinder of water is quiescent, and holds the elevator car or platform stationary. When the elevator-rope is moved and the valves *d* and *e* turned so as to bring the ports 9 and 5 and 8 and 12 opposite to each other, the water is drawn from the top of the cylinder by the pipe *f'* to the valve *e* and induction *n*, and the water is forced from the pump by *n'*, *d*, 9, and 5, into the pipe *f*, and the lower end of the cylinder, and the piston is moved upwardly. When the elevator-rope is so moved as to turn *d* and *e* to bring the ports 7 and 11 and 10 and 6 together the water is forced from *d* through *f'*, and drawn from *f* through 7 and 11 into *e*, and thence by *n* to the pump. By this arrangement the hoisting, lowering, and sustaining of the elevator are entirely under control of the attendant, and the pump will run continuously.

As a precaution to prevent injury, if the cylinder-valves are not turned the proper distance I employ a pipe, *o*, connecting the water-ways *n* and *n'*, and in this pipe *o* there is a safety-valve, *p*, preferably operated by a spring that yields and allows the water to churn around through the pump if the maximum pressure is exceeded.

I remark that the cylinder-valves *d* and *e* are preferred; but slide or puppet valves may be used in place of the cylinders, the ports being arranged, in connection with the water-ways, so as to effect the same movement of the water by the pump.

The reservoir *k* is above the pipe *f*, leading from the lower side of the cylinder, and a pipe and valve, *l*, connect the reservoir to the pipe *f*. This valve should open automatically by any

minus pressure; hence, if there is any leakage of water, the deficiency will be supplied by water drawn in from said reservoir *k*, so as to keep the cylinder and water-ways all full.

I am aware that air has been forced into the hoistway below the car to raise it, or allowed to pass above the car as it descends, and that a valve has been operated from the car to direct the air.

I claim as my invention—

1. The combination, with the hydraulic-elevator cylinder and piston of a pump, water-ways and valves arranged and acting, substantially as set forth, to transfer the water from one side of the elevator-piston to the other and move that piston in either direction, or to allow the water to be confined, and a connection from the outlet to the inlet of the pump, whereby the pump continues its movement when the elevator is stationary, as set forth. 60

2. The combination, with the elevator cylinder and piston, of the water-ways *f* *f'* *f''* *f'''*, valves *d* *e*, connecting-pipe *i*, pump, and mechanism connecting the valves *d* and *e* with the hand-rope of the elevator, substantially as 65 set forth.

3. The combination, in an elevating apparatus, of the hydraulic cylinder *a*, pump, water-ways connecting the cylinder and pump, valves in those water ways, constructed and 70 acting substantially as set forth, and a reservoir and inlet valve to supply water and compensate leakage, as set forth.

Signed by me this 14th day of January, A. D. 1880.

DAVID P. DAVIS.
